Application April 8, 1947, Serial No. 739,990

2 Claims. (Cl. 81—72)

1

This invention relates to tools for removing lamp bases from their sockets.

The primary object of the present invention is the provision of a tool which is particularly well adapted for use in removing lamp bases from sockets from which it is difficult to remove the lamp bases, which is frequently the case, especially in outdoor electric light signs due to corrosion of the lamp bases in the sockets, or due to paint or other causes.

Another object of the invention is to provide a lamp base removing tool which is well adapted to remove the lamp base from the socket by unscrewing the base from the socket, and which is of such construction and operation as to facilitate the removal of the lamp base from the tool after the lamp base is removed from the socket.

A further object is generally to provide a lamp base removing tool which is of simple construction and which is highly effective for its purposes and easy to use.

Another object is the provision of a tool for cleaning the inner surfaces of electric light sockets.

The above and other objects, features and advantages of the present invention will be fully understood from the following description considered in connection with the accompanying illustrative drawings.

In the drawings:

Fig. 1 is a side view of a lamp base removing tool embodying the present invention;

Fig. 2 is a view similar to Fig. 1 showing the tool carrying a lamp base which has been removed from a socket;

Fig. 3 is a view of the tool partly in elevation and partly in section, the positions of relatively movable parts of the tool corresponding to the positions shown in Fig. 1.

Fig. 4 is an end view of the tool;

Fig. 5 is a side view, in elevation, of a tool embodying another form of the invention;

Fig. 6 is a longitudinal sectional view on the line 6—6 of Fig. 5;

Fig. 7 is a sectional view on the line 7—7 of Fig. 6;

Fig. 8 is a sectional view on the line 8—8 of Fig. 6;

Fig. 9 is a side view of one of the gripping elements.

Referring now to the drawings and first to the form of the invention illustrated in Figs. 1 to 4, the tool 10 embodying the present invention comprises a lamp base gripping member 12 and an operating member 14 for conditioning the grip-

2

ping member 12 to grip and release the lamp base and for actuating the gripping member for removing the lamp base from the socket.

The gripping member 12 is preferably formed of spring steel and comprises a part or holder 16 which is preferably cylindrical and which is internally screw-threaded as indicated at 18. Gripping member 12 is radially expandable and contractable and for this purpose is provided with a plurality of circumferentially spaced longitudinal slots 20 which extend to the free outer end of said gripping member forming a plurality of resilient segments 22 which extend longitudinally of the gripping member and constitute lamp-base gripping elements. It will be understood that the gripping member 12 is peripherally continuous except in the slotted portion which provides the gripping elements 22. The outer end portion of gripping member 12 is externally screw-threaded as indicated at 24 to fit the internal screw-threaded surface of a lamp base which is indicated at B in Fig. 2. It will be understood that screw-threaded portion 24 of the gripping member is cylindrical and that in its normal or contracted condition it may be inserted within or threaded into the screw-threaded shell of the lamp base after a sufficient amount of the glass of the lamp bulb and the material which was used for securing the lamp bulb in the base have been removed. Preferably, but not necessarily, the diameter of threaded portion 24, in its normal contracted condition, is such that it is insertable into the base only by screwing it into the lamp base. A shoulder 26 is provided on the gripping member to limit the extent of insertion of part 24 of the gripping member in the lamp base.

The operating member 14 comprises a rigid stem or spindle 28 having a threaded portion 18 which is in screw-threaded engagement with the threaded portion 30 of the lamp base gripping member 12. Said stem 28 has an outwardly flaring or inwardly tapering outer end portion 32 which is of circular cross section and which is in engagement with the outwardly flaring or bevelled inner surface 34 of the outer end portion 24 of the gripping member so that as a result of relative rotation of members 12 and 14 in a predetermined direction end portion 32 of operating member 14 moves axially or longitudinally inwardly of the outer end portion 24 of gripping member 12 thereby radially expanding the latter for securely gripping the lamp base B internally thereof, with the raised screw portions of part 24 in the grooves of the screw-threads of

the lamp base internally thereof. It will be understood that parts 24 and 32 are concentric or coaxial.

Provision is made for releasably holding members 12 and 14 against relative rotation. For that purpose a locking member 36 which as here shown is in the form of a sleeve has a sliding fit on spindle 14 but is held against rotary movement thereon by a pin 38 which is fixed to said spindle and which projects into a slot 40 provided in said locking member. The adjacent end of gripping member 12 is provided with one or more notches 42 in which a companion integral projection 44 of locking member 36 has a removable fit, in one position of said locking member longitudinally of spindle 28 for releasably preventing relative rotation between gripping member 12 and operating member 14. A spring pressed ball 46 is disposed within a lateral groove 48 in spindle 28 and is engageable in either of two recesses 50 and 52, respectively, for releasably holding the locking member in its locking and retracted positions, respectively. A rigid pin 54 is fixed to spindle 14 and projects laterally thereof for engagement with the adjacent edge 56 of part 16 of the gripping member 12 for limiting the movement of spindle 28 longitudinally toward the outer split end of member 12. It will be understood that when pin 54 is in engagement with edge 56 of part 16 of member 12, the lamp base gripping member is in its normal or radially contracted condition. Spindle 28 is provided with a cross pin or handle 58 for actuating the tool and for use in effecting the relative rotation of members 12 and 14.

Figs. 1 and 3 show relative positions of the parts of the tool in which the threaded part 24 of the tool is insertable into the lamp base B, the screw-threaded portion 24 of the tool being radially contracted. The screw-threaded shell or socket in which the lamp base is mounted and from which it is to be removed by the tool is not shown since sockets of this type are well known.

The lamp base being in its socket is removed therefrom in the following way: The threaded end portion 24 of the tool, being constructed so that it can be threaded into the base internally thereof is rotated by operation of the spindle 14 by means of the handle 58, the locking member 36 being in its locking position as shown in Fig. 1. This is effected by turning the tool in the direction of arrow A in Fig. 1, preferably through about three revolutions. Then the locking member 36 is released from the gripping member 12, as illustrated in Fig. 2 and member 14 is then rotated in the opposite direction as indicated by the arrow B in Fig. 2. The rotation of member 14 in this last mentioned direction results in the radial expansion of screw-threaded portion 24 of the outer gripping member so that the latter securely grips the lamp base internally thereof whereby continued operation thereafter of the tool in the same direction is effective to unscrew the lamp base from the socket for removing the lamp base therefrom.

After the lamp base is removed from its socket spindle 28 of operating member 14 is turned in the opposite direction, say in the direction of arrow A in Fig. 1 while the gripping member 12 is held against rotation, for example, by holding the lamp base B which is mounted on said gripping member, until the radial pressure of the screw-threaded portion 24 on the internal screw-threaded surface of the lamp base is released. Then the locking member 36 is returned to its

locking position to prevent relative rotation of members 12 and 14 so that removal of the lamp base B from the tool is facilitated by unscrewing said lamp base from the threaded portion 24 of the tool. In case more than average difficulty is encountered in removing the lamp base from its socket by turning the handle 28 by hand, a wrench or other suitable tool may be applied to member 12, and for this purpose portion 16 of said member is provided with a hexagonal or other part 60 which may be engaged by a wrench and thereby rotated. The outer end of spindle 28 is preferably recessed as indicated at 62 in Fig. 3 to receive parts of the lamp or lamp securing material which might not have been removed from the lamp base preliminary to the insertion of the tool in the lamp base as referred to above.

The tool of the present invention can be used for cleaning electric lamp sockets as well as for removing lamp bases therefrom. In this connection, it will be understood that the tool may be inserted in the socket so as to engage the threaded portion 24 of the tool with the screw-threaded shell of the socket internally thereof. The portion 24 may be expanded, if desired, to provide the required fit between the outer surface of said portion and the inner threaded surface of the socket shell so that rotation of the tool results in scraping and cleaning the said surface of the socket. Thus the tool is particularly well adapted for removing paint, corrosion and other foreign material from the inner surface of the socket shell whereby to clean the same and thereby improve the electrical conducting condition thereof.

In the tool 10A, embodying the presently preferred form of the invention illustrated in Figs. 5 to 9, the gripping member 70 comprises a plurality of individual gripping elements 72, which are initially separate from the holder part 74, instead of being integral with the holder part 16 as are the gripping elements 22 in the above described tool 10. Each gripping element 72 is in the form of a rigid bar and is assembled with the other gripping elements in circumferential relation around the operating member 76 and with the inner end portions of said gripping elements within the holder part 74. The latter is provided with an internal peripheral groove 78, and each gripping element 72 has a lateral end projection 80 which projects into said groove and is thereby held against movement axially of said part 74. Provision is made for holding elements 72 in circumferentially spaced relation, the means provided for this purpose comprising the circular plates 82 and 84 which surround member 76 and are spaced from each other longitudinally of member 76, said plates having central openings 86 and 88 in which member 76 has a sliding fit. Each plate has a plurality of circumferentially spaced recesses 90, in its outer peripheral edge, and each element 72 has a pair of longitudinally spaced recesses 92 in its inner edge. In the assembled relation of elements 72 and said plates 82 and 84, the latter engage said elements in the recesses 92 thereof and the elements engage said plates in the recesses 90 thereof, so that said elements are held by said plates in the circumferentially spaced relation thereof and so that said plates are held in fixed spaced relation longitudinally of said elements. The interengagement between elements 72 and plates 82 and 84 is with sufficient clearance to enable limited radial movement of said elements to their circumferentially expanded and contracted posi-

tions, corresponding to the radial movement of gripping elements 22 of tool 10, as described above, for operative engagement with and release from the lamp base. Plate 82 is provided with a lateral key projection 94 which engages holder 74 in a recess 96 to prevent turning of said plate in said holder, thus holding elements 72 in fixed relation circumferentially of holder 74.

The operating member 76 has a screw-threaded portion 98 which is in screw-threaded engagement with the internally screw-threaded part 100 of holder 74, so that relative turning of members 74 and 76 results in relative longitudinal or axial movement of said members. Operating member 76 has an outwardly flaring or inwardly tapering conical end portion 102 for engagement with the bevelled ends 104 of gripping elements 72 for moving said elements radially outwardly to their expanded or lamp-base gripping positions. It will be understood that when member 76 is rotated in relation to holder 74 in such direction that part 102 moves axially of the holder toward end 106 thereof, said part 102 engages the bevelled ends 104 of elements 72 for moving them to their circumferentially-expanded positions, and it will be noted that the outward radial movement of said elements is limited by the engagement of the edge surfaces 108 of the latter with the inner peripheral surface 110 of holder 74. Thus, in the final circumferentially expanded positions of elements 72, the latter are clutched to the holder 74.

When, as here shown, the tool is designed for removing lamp bases of the screw-threaded type from screw-threaded socket shells, elements 72, like elements 22 of tool 10 are screw-threaded, collectively, for engagement of the screw-threaded portions 112 of said elements internally of the lamp base as described above in respect to the operation of tool 10. When the gripping member is inserted into the lamp base, the elements 72 are in their fully circumferentially-contracted positions, part 102 being at its extreme position away from end 106 of holder 74 by reason of the engagement of the locking member 114 with holder 74 in a manner similar to the action of locking member 36 of tool 10. Locking member 114 has two diametrically opposite projections 116 which engage holder 74 in the diametrically opposite recesses 118 provided in the edge 117 of said holder. Locking member 114 is movable longitudinally of member 76, in the same way as said locking member 36, into and out of engagement with holder 74, and has the pin and slot connection and spring-pressed holder shown at 38, 40, 46 and 48 in Fig. 3 in reference to tool 10. In addition, locking member 114 has a finger piece 119 which may be engaged by the user's fingers, when the tool is held in his hand with the handle 120 against his palm, for retracting the locking member from engagement with holder 74. Handle 120 is removably secured to the end of operating member 76 in any suitable way as by a screw 124, said end of member 76 having a non-circular part 126 which fits non-rotatably into a corresponding shaped opening 128 in the handle.

The tool 10A is operable in the same way as the tool 10 for removing lamp bases from their sockets as hereinbefore described with reference to tool 10. It will be noted that the holder 74 is provided with a non-circular part 129, here shown as hexagonal, to provide a wrench-grip as described above with reference to part 60 of tool 10.

The tool 10A, like the tool 10, may also be used for cleaning electric lamp sockets. When used for this purpose, elements 72 are in partially circumferentially-expanded condition. Preferably said elements are in the positions to which they are moved by part 102 of the operating member as a result of one complete turn or revolution of said member in relation to holder 74 for causing movement of part 102 toward end 106 of said holder. During the operation of the tool for cleaning the socket, holder 74 is locked to member 76 by locking member 114.

It will be noted that the outer ends of elements 72 are also bevelled at their outer edges as indicated at 130 so that the gripping member considered as a whole has an inwardly tapering outer end to facilitate insertion of the gripping member into the lamp base or into the lamp base socket. It will be understood that the tool 10A is operated substantially in the same way as tool 10 either for removing a lamp-base from its socket or for cleaning a socket. If desired, either end of handle 120 may be pointed for use in cleaning cement and/or glass from the lamp base so that the gripping member may be inserted into the base, or for the same purpose, a suitable device (not shown) may be secured to handle 120, and in either case the tool 10A may be held in the hand for the cleaning operation by gripping the holder 74 in the palm of the hand.

Holder 74 is preferably made in one piece, as shown, and assembled with member 76, gripping elements 72 and plates 82 and 84, before locking member 114 and handle 120 are attached to or mounted on said operating member. In this connection, it will be understood that there is sufficient clearance between elements 72 and said plates and between said elements 72 and holder 74 to enable all of these parts to be assembled together into a unit and then assembled as a unit with member 76 by inserting the latter through the openings 86 and 88 in the plates and through the holder 74. After holder 74, elements 72 and plates 82 and 84 are assembled as a unit on member 76, locking member 114 is placed in position on and secured to member 76, and finally handle 120 is attached. It will be noted that elements 72 cannot be removed unless operating member 76 is withdrawn from the assembly and that this cannot be done without first removing locking member 114 and handle 120.

It will be understood that while the tools embodying the present invention are intended primarily for use in connection with lamp bases of the screw-threaded type and are therefore provided with screw-threaded gripping members, it is within the scope of the present invention to omit the screw-threads from said gripping members when the tool is designed for use with other types of lamp bases, for example lamp bases which have bayonet type of connection with a lamp socket of the bayonet-slot type. In the latter event, the gripping member on certain of the base-gripping elements thereof may have a lateral projection to engage one or more lateral projections or protuberances which are usually present in the internal peripheral surface of the lamp base in line with the projections which engage in the bayonet-slots of the socket.

This application is a continuation in part of our application, Serial No. 669,061, filed May 11, 1946.

It will be understood that various changes in the details of construction and in the arrange-

ment of parts may be made without departing from the underlying idea or principles of our invention within the scope of the appended claims.

Having thus described our invention, what we claim and desire to secure by Letters Patent is:

1. A tool for removing a screw-threaded lamp base from a threaded socket comprising a holder member having an internally screw-threaded part, a rod having a screw-threaded stem in screw-threaded engagement with said part, said holder member having a tubular portion extending axially from said screw-threaded part, said tubular portion being provided with an internal peripheral groove, a plurality of circumferentially disposed gripping elements carried by said holder member in said tubular portion thereof, each of said gripping elements being provided in its outer surface with a lateral end projection removably positioned in said groove for preventing relative axial movement of said holder member and said gripping elements, said gripping elements being radially movable in relation to said holder member and extending axially beyond the free end of said tubular portion thereof, said gripping elements being externally screw-threaded in the extended portions thereof for engagement with the screw-thread of the lamp base internally of the latter, each of said gripping elements comprising a longitudinally extending bar having an inner surface portion which flares outwardly toward the outer end thereof and being provided with longitudinally spaced recesses disposed on the inner surface thereof above said flared portion, and a pair of circular centrally apertured plates each provided with a plurality of circumferentially spaced recesses in the outer peripheral edges thereof, said plates engaging said gripping elements in the longitudinally spaced recesses thereof and said gripping elements engaging said plates in the circumferentially spaced recesses thereof whereby said gripping elements are retained by said plates in the circumferentially spaced relation thereof and said plates are held in fixed spaced relation longitudinally of said elements, said interengagement between said gripping elements and plates enabling limited radial movement of said gripping elements to their circumferentially expanded and contracted positions for operative engagement with and release from the lamp base,

10 the upper one of said plates being provided with a lateral key projection, said tubular portion being provided on its inner surface with a recess in which said key projection is disposed for preventing the turning of said upper plate in said holder member, said rod extending through the apertures in said plates and having a sliding fit therein, and said rod being provided with an inwardly tapering part at the end thereof below the screw-threaded stem thereof, said inwardly tapering part being in juxtaposition to said outwardly flaring surface portions of said gripping elements whereby rotation of said rod in relation to said holder member in a direction for unscrewing the lamp base from its socket results in axial movement of said inwardly tapered part toward the end of said holder member opposite the free end of said tubular portion thereof and in a radial outward movement of said gripping elements to clamp the latter radially against the lamp base so that continued rotation of said rod in said direction causes the lamp base to be unscrewed from its socket.

20 2. A tool for removing a screw-threaded lamp base from a socket, as set forth in claim 1, wherein said gripping elements are provided with bevelled outer surface portions at the outer ends thereof for facilitating the insertion of said elements into the lamp base or into the lamp base socket.
